(57) CLAIM

The ornamental design for a bottle, as shown and described.

DESCRIPTION

FIG. 1 is a perspective view of a bottle, embodying our new design;

FIG. 2 is a front view thereof;

FIG. 3 is a top plan view thereof;

FIG. 4 is a bottom view thereof; and,

FIG. 5 is an exploded perspective view thereof.

The broken lines shown in the drawings are for illustrative purposes only and form no part of the claimed design.

Back view and side views are omitted because these are identical to a front view.
